Primary Examiner — Paula Greene(74) Attorney, Agent, or Firm — Pollack, P.C.(57) CLAIM

The ornamental design of a funeral urn, substantially as shown and described.

DESCRIPTION

FIG. 1 is a perspective view of a specific, illustrative funeral urn showing my new design;

FIG. 2 is a front view of the urn shown in FIG. 1;

FIG. 3 is a rear view of the urn illustrated in FIG. 1;

FIG. 4 is a side view of the urn shown in FIG. 1, the opposite side view being a mirror image thereof;

FIG. 5 is a plan view of the urn set forth in FIG. 1; and,

FIG. 6 is a bottom view of the urn illustrated in FIG. 5.
